PISTON GRINDING ATTACHMENT

Ralph E. Price and Harold E. Balsiger, Waynesboro, Pa.,
assignors to Landis Tool Company, Waynesboro, Pa.
Filed Sept. 14, 1965, Ser. No. 487,156
8 Claims. (Cl. 51—101)

ABSTRACT OF THE DISCLOSURE

The disclosure of this application relates to the grinding of automotive pistons, particularly those having a tapered as well as an elliptical contour. Pistons having an elliptical contour are ground on a machine which is basically a cam grinder, in that, the work is supported on a cradle for oscillation toward and from the grinding wheel in accordance with the contour of a master cam. The axis of oscillation is parallel to the axis of rotation of the work drive spindle. The apparatus of this application differs from the conventional piston grinder, in that, the axis of oscillation intersects the axis of rotation of the work drive spindle and workpiece and the oscillating movement of the workpiece occurs about the intersection of the two axes as well as about the axis of oscillation. It is this angular relation between the two axes which provides the tapered portion of the contour of the workpiece.

The present invention relates to apparatus for grinding non-circular workpieces, particularly automotive pistons having a form generally referred to as "tapered elliptical."

In a tapered elliptical piston, the degree of taper changes progressively between arcuately spaced points on the skirt of the piston. The small diameter at the head end of the skirt is smaller than the small diameter at the open end of the skirt.

In order to form this type of piston by a grinding or other machining operation, the piston must be oscillated toward and from the cutting tool about a predetermined point with relation to the piston, preferably a point on its axis.

In the past, this type of piston has been ground on more or less conventional grinding machines provided with an attachment whereby the swivel table is oscillated about the vertical swivel stud provided for swivelling the table for taper grinding. The piston is rotatably supported on said table between a headstock center and a footstock center in a position longitudinally spaced from the axis of the swivel stud. Oscillation of the piston about said swivel stud axis by an eccentric or master cam during a grinding operation, provides the desired taper on the skirt of the piston. This is a progressively varying taper and, therefore, at each degree of rotation, the skirt of the oscillating piston is at a different angle to the face of the grinding wheel.

The oscillation of the piston toward and from a grinding wheel is in a substantially horizontal plane between two positions, in one of which the surface of the piston skirt may be parallel or at a slight angle to the face of the grinding wheel, and in the other position, at a greater angle to the face of the grinding wheel. The range of oscillation is determined by the difference between the maximum and minimum diameters of the master cam.

The principal disadvantage of this attachment is that it requires movement of a relatively large mass consisting of the swivel table, headstock and footstock mounted thereon about a mechanical pivot, and the corresponding forces required to overcome as well as to resist inertia.

It is, therefore, an object of the present invention to provide improved means for oscillating a workpiece rela-

2

tive to a cutting tool to produce a tapered elliptical form on said workpiece.

Another object is to provide a compact attachment for machining tapered elliptical workpieces.

Another object is to provide apparatus in which only the work drive spindle and its immediate support are oscillated.

FIG. 1 is a front elevation, partly in section.

FIG. 2 is a right hand end elevation.

FIG. 3 is a plan view.

FIG. 4 is a diagrammatic sketch showing the relation between the master cam, follower, workpiece and grinding wheel.

This invention provides a simplified mechanism for grinding a tapered elliptical form on a workpiece while utilizing fewer and lighter parts than previous apparatus used for this purpose. It utilizes the apparatus disclosed in co-pending application, Ser. No. 285,985, filed June 6, 1963, now U.S. Patent 3,247,619, granted Apr. 26, 1966, to which reference may be made to details of structure and operation.

The apparatus disclosed in this application is modified in a novel manner to provide the oscillating movement necessary to produce the tapered elliptical form on the workpiece. The vertical mechanical pivot which is an essential element of the old apparatus is eliminated, but its function is retained in the stationary or non-oscillating point on the piston axis. The relatively large flat oscillating bearing surface of the work table on the carriage of the old-type machine is replaced by the relatively small cylindrical cradle pivot shaft of the above mentioned application. The modification of the device disclosed in the application consists in mounting the cradle pivot shaft at an angle instead of parallel to the work drive spindle. The angle of the pivot shaft must be such that the axis of the pivot shaft intersects the axis of the piston at a predetermined point about which the piston oscillates toward and from the grinding wheel to produce the required taper on the piston skirt.

The reduction in the mass to be oscillated is due in large part of the elimination of a footstock and swivel table which, in turn, is due to the use of an improved chuck, whereby the workpiece is supported only at the head end. Supporting the workpiece only at the head end also eliminates deformation of the workpiece which occurs when the workpiece is supported between a headstock and a footstock.

In the drawings, the work drive or headstock spindle 10 is rotatably supported in bearings 11 in spindle housing 12. Spindle housing 12 is mounted for longitudinal adjustment on a cradle 13. Cradle 13 is arranged to be supported by pivot shaft 14 in pivot shaft base 15.

Pivot shaft base 15 is arranged to support pivot shaft 14 at a predetermined angle relative to spindle 10. Base 15 is mounted for longitudinal movement with cradle 13 between bed 16 and spindle housing 12 to provide for slight adjustment of point X where axis P of pivot shaft 14 intersects the axis S of spindle 10 and workpiece W. The location of point X relative to workpiece W along with the lift or drop of a master cam, determines the amount or degree of taper to be ground on said workpiece. This adjustment provides for accurate positioning of pivot point X at assembly and also for pistons of different taper within the range of adjustment.

Spindle 10 is driven through a suitable belt and pulley arrangement by the motor 30. Master cam 20 on spindle 10 has a contour which includes a lift substantially greater than that to be applied to workpiece W. Follower roller 21 is supported on a pivoted arm 50 for contact with the master cam 20. Arm 50 is pivoted at a point (not shown) near its upper end so that the oscillating movement of the follower roller 21 in response to the rotation of master

cam 20 is substantially reduced. This reduced movement is transmitted through a leaf spring 51 and a flexible member 52 to bracket 53 attached to cradle 13. Cradle 13 is mounted for oscillation on shaft 14. Thus, any error in the contour of master cam 20 is reduced by the lever ratio 5 in arm 50 before it is transmitted to workpiece W.

The means for rotatably supporting workpiece W in operative relation with grinding wheel 25 consists of a chuck 40 arranged to grip the head portion of workpiece W in such a manner that the gripping force is not transmitted to the portion of the workpiece being ground. Chuck 40 is the sole means for supporting workpiece W during a grinding operation, thus eliminating the need for a conventional footstock support member which applies a holding pressure to the portion of the workpiece being ground with the result that the workpiece is deformed during a grinding operation with a corresponding error in the contour of the finished workpiece.

The location of the intersection of the axis of workpiece W and the axis of oscillation of the workpiece and spindle 10, is determined by the following equation:

$$Z = \frac{AL}{A-B}$$

where:

Z is the distance from the small end 1 of the piston skirt to the point of intersection X of said axes,
A is the lift or difference in radius between the major and minor axes at the small end 1 of the piston skirt,
B is the lift or difference in radius at the large end 2 of the piston skirt, and
L is the distance between points 1 and 2 at which dimensions A and B are measured.

Operation

Rotation of spindle 10, master cam 20 and workpiece W by motor 30 causes said parts to oscillate in a manner determined by the angular position of pivot shaft 14 so that the left or head end of workpiece W moves through 40 a greater distance toward and from grinding wheel 25 than its right or open end.

At one limit of oscillation, the surface of workpiece W is parallel to the face of grinding wheel 25 or at a slight angle thereto, depending on the location of the zone of oscillation. As workpiece W moves toward grinding wheel 25 about the swivel point X (FIG. 4), the angular relation between workpiece W and grinding wheel 25 changes progressively so that at each degree of rotation, workpiece W is ground to a different taper. The maximum taper is 50 produced when workpiece W reaches the limit of its oscillation toward grinding wheel 25.

We claim:

1. In a machine for grinding non-cylindrical workpieces,

- (a) a grinding wheel,
- (b) a work support comprising
- (c) a housing,
- (d) a work drive spindle rotatably mounted in said housing,
- (e) means on said spindle for rotatably holding a workpiece in operative relation with said grinding wheel,
- (f) a master cam on said spindle,
- (g) a follower roller for engaging the contour of said master cam,
- (h) a cradle for supporting said housing and spindle for oscillation in response to rotation of said master cam against said follower roller,
- (i) the axis of oscillation of said cradle being at an angle to the axis of said spindle.

2. In a machine for grinding non-cylindrical workpieces,

- (a) a grinding wheel,
- (b) a work support comprising
- (c) a housing,

- (d) a work drive spindle rotatably mounted in said housing,
- (e) means on said spindle for rotatably holding a workpiece in operative relation with said grinding wheel,
- (f) a master cam on said spindle,
- (g) a follower roller for engaging the contour of said master cam,
- (h) and means for grinding a tapered elliptical surface on said workpiece comprising
- (i) a cradle for supporting said housing and spindle for oscillation in response to rotation of said master cam against said follower roller,
- (j) the axis of oscillation of said cradle intersecting the axis of said spindle at a predetermined position relative to said workpiece.

3. In a machine for grinding non-cylindrical workpieces,

- (a) a grinding wheel,
- (b) a work support comprising
- (c) a housing,
- (d) a work drive spindle rotatably mounted in said housing,
- (e) means on said spindle for rotatably holding a workpiece in operative relation with said grinding wheel,
- (f) a master cam on said spindle,
- (g) a follower roller for engaging the contour of said master cam,
- (h) a cradle for supporting said housing and spindle for oscillation in response to rotation of said master cam against said follower roller,
- (i) the axis of oscillation of said cradle being at an angle less than ninety degrees to the axis of said spindle.

4. In a machine for grinding non-cylindrical workpieces,

- (a) a grinding wheel,
- (b) a work support housing,
- (c) a work drive spindle rotatably mounted in said housing,
- (d) means on said spindle for rotatably supporting a workpiece in operative relation with said grinding wheel,
- (e) a master cam on said spindle,
- (f) a follower roller for engaging the contour of said master cam,
- (g) means for oscillating said housing and spindle in response to rotation of said master cam against said follower roller,
- (h) means to grind a tapered elliptical surface on said workpiece comprising
- (i) a support for said spindle mounted for oscillation about an axis at an angle to the axis of said spindle,
- (j) said axes intersecting at a point determined by the equation

$$Z = \frac{AL}{A-B}$$

where:

Z is the distance from the small end of the piston skirt to the point of intersection of said axes;

A is the lift or difference in radius between the major and minor axes at the small end of the piston skirt;

B is the lift or difference in radius at the large end of the piston skirt, and

L is the distance between the points at which the dimensions A and B are measured.

5. In a machine for machining tapered, non-cylindrical workpieces,

- (a) a tool,
- (b) a work support comprising
- (c) a housing,
- (d) a work drive spindle rotatably mounted in said housing,
- (e) means on said spindle for rotatably holding a

- workpiece at one end only in operative relation with said tool,
 (f) a master cam on said spindle,
 (g) a follower roller for engaging the contour of said master cam,
 (h) a cradle for supporting said housing and spindle for oscillation in response to rotation of said master cam against said follower roller,
 (i) the axis of oscillation of said cradle intersecting the axis of said workpiece.
6. In a machine for machining tapered, non-cylindrical workpieces,
 (a) a tool,
 (b) a work support comprising
 (c) a housing,
 (d) a work drive spindle rotatably mounted in said housing,
 (e) means on said spindle for rotatably holding a workpiece at one end only in operative relation with said tool,
 (f) a master cam on said spindle,
 (g) a follower roller for engaging the contour of said master cam,
 (h) a cradle for supporting said housing and spindle for oscillation in response to rotation of said master cam against said follower roller,
 (i) the axis of oscillation of said cradle intersecting the axis of said workpiece at a point in space which determines the taper to be produced on said work-piece.
7. In a machine for grinding non-cylindrical workpieces,
 (a) a grinding wheel,
 (b) a work support housing,
 (c) a work drive spindle rotatably mounted in said housing,
 (d) means on said spindle for rotatably supporting a workpiece in operative relation with said grinding wheel,

5

10

15

20

25

30

35

- (e) a master cam on said spindle,
 (f) a follower roller for engaging the contour of said master cam,
 (g) means for oscillating said housing and spindle in response to rotation of said master cam against said follower roller,
 (h) and means to grind a tapered elliptical surface on said workpiece comprising
 (i) a support for said spindle mounted for oscillation about an axis at an angle less than ninety degrees to the axis of said spindle.
8. A machine for grinding a non-cylindrical work-piece comprising
 (a) a work support for holding a workpiece in operative relation to a grinding wheel,
 (b) said support including workpiece holding means on a work drive spindle rotatably mounted in a housing,
 (c) means for oscillating said housing and spindle including a master cam on the spindle and engaging, by its periphery, a cam follower, and
 (d) a pivot shaft pivotally supporting the master cam and spindle,
 (e) the axis of the pivot shaft being at an angle to the axis of the spindle.
